(57) **CLAIM**

The ornamental design for a portable electronic device with surface mount, as shown and described.

DESCRIPTION

FIG. 1 is a perspective view of a portable electronic device with surface mount showing the new design, showing the surface mount only for ease of illustration;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is a perspective view of the portable electronic device combined with surface mount;

FIG. 9 is a front view thereof;

FIG. 10 is a back view thereof;

FIG. 11 is a side view thereof;

FIG. 12 is another side view thereof;

FIG. 13 is a top view thereof;

FIG. 14 is a bottom view thereof;

FIG. 15 is a perspective view thereof, showing the surface mount removed from the portable electronic device and attached to a surface during mounting; and,

FIG. 16 is a perspective view thereof, showing the portable electronic device combined with the mount and attached to a surface.

The broken lines and the unshaded regions bounded by broken lines show portions of the portable electronic device with surface mount that form no part of the claimed design. FIGS. 15 and 16 showing a surface on which the portable electronic device with surface mount mounts, illustrates environment and forms no part of the claimed design. Non-oblique line shading is meant to show contour and not surface ornamentation.
